UNITED STATES PATENT OFFICE

148,474

DESIGN FOR A HANDBAG OR SIMILAR ARTICLE

Florence Kuhlman, New York, N. Y.

Application April 23, 1947, Serial No. 138,549

Term of patent 7 years

(Cl. D87—3)

To all whom it may concern:

Be it known that I, Florence Kuhlman, a citizen of the United States of America, residing in New York, county of New York and State of New York, have invented a new, original, and ornamental Design for a Handbag or Similar Article, of which the following is a specification, reference being had to the accompanying drawing, forming part thereof.

Fig. 1 is a front perspective view of a handbag or similar article, showing my new design.

Fig. 2 is a rear perspective view thereof illustrating the handbag in open position.

Fig. 3 is a top plan view illustrating the inside of the handbag.

Fig. 4 is a front perspective view as shown in Fig. 2 with the handles and handle bar removed.

I claim:

The ornamental design for a handbag or similar article, substantially as shown.

FLORENCE KUHLMAN.
